CLAIM

The ornamental design for an end mill, as shown and described.

DESCRIPTION

FIG. 1 is a plan view of the end mill;

FIG. 2 is a front view thereof;

FIG. 3 is a bottom plan view thereof;

FIG. 4 is a rear view thereof;

FIG. 5 is a left-hand side view thereof;

FIG. 6 is a right-hand side view thereof;

FIG. 7 is a sectional view taken generally along line 7—7 of FIG. 2; and,

FIG. 8 is a sectional view taken generally along line 8—8 of FIG. 5.

The broken lines are included for the purpose of illustrating non-claimed subject matter and form no part of the claimed design.
